UNITED STATES PATENT OFFICE

113,885

DESIGN FOR A PASSENGER VESSEL

Harry B. Spear, Cradock, Va.

Application August 5, 1938, Serial No. 79,135

Term of patent 14 years

To all whom it may concern:

Be it known that I, Harry B. Spear, a citizen of the United States, residing at Cradock, in the county of Norfolk and State of Virginia, have invented a new, original, and ornamental Design for a Passenger Vessel, of which the following is a specification, reference being had to the accompanying drawings, forming part thereof.

Fig. 1 is a perspective view showing my new design for a passenger vessel;

Fig. 2 is a side elevational view and
Fig. 3 is a top plan view thereof.
The dominant features of my design are shown in solid black lines in the drawings.

I claim:

The ornamental design for a passenger vessel, as shown and described.

HARRY B. SPEAR.
